UNITED STATES PATENT OFFICE

EDWIN WILLIAM ABRAHAMSON, OF BUFFALO, NEW YORK, ASSIGNOR TO TWIN-PLEX METAL MANUFACTURING CORPORATION, OF BUFFALO, NEW YORK, A CORPORATION OF NEW YORK

WINDOW

Application filed December 5, 1927. Serial No. 237,738.

This invention relates to a window, and more particularly to a window in which the principal parts are constructed of sheet metal.

5 One of the objects of this invention is to provide a window in which the frame has an integral wind break which upon being built into the wall of a building by masonry or the like operates not only to effectively prevent the wind and weather from entering between the frame and wall but also strengthens and stiffens the frame and simplifies and cheapens the construction.

10 Another object of this invention is to provide a window frame in which the face plates of the jambs are readily removable for convenience of assembly and repairs and also to afford easy access to the boxes formed by the jambs for taking care of the sash 20 weights and other parts contained therein.

Another object of this invention is to provide sash hanging bars or runners on the jambs for guiding the sliding sash which are rigid and weather tight and which will 25 maintain the sashes parallel with the frame while in a normal position and still permit the sashes to be reversed freely and easily.

Another object of this invention is to provide improved parting strips or stops between the runners or hanging bars for the 30 upper and lower sashes which strips in co-operation with the runner bars form a weather tight joint and still permit the sashes to be raised and lowered freely.

35 A further object of the invention is to improve the joint between the sill of the window frame and the lower sash when the latter is closed so as to strengthen and cheapen the same and also render the same weather tight when closed and permit the discharge to the exterior of any water which may enter the joint.

40 A still further object of this invention is to so construct the head of the same so that the face plate of the same is removable and the sash lines and guide pulleys are easily accessible for inspection, adjustment and repairing.

45 This invention has the added object of so organizing the sash balancing mechanism

that one weight serves to support both sides of the same sash and thus simplifies the construction, lessens the cost and reduces the liability of getting out of order.

In the accompanying drawings:

55 Figure 1 is a perspective view of a window embodying my improvements showing the sashes in an open position and one of the jambs partly broken away. Figure 2 is a horizontal section taken on line 2—2, Fig. 1. 60 Figure 3 is a perspective view showing parts of the mechanism for balancing the sashes. Figure 4 is a fragmentary vertical section, on an enlarged scale, taken on line 4—4, Fig. 1. Figures 5, 6 and 7 are fragmentary horizontal sections, on an enlarged scale, taken on the correspondingly numbered lines in Fig. 1. Figure 8 is a fragmentary vertical section, on an enlarged scale, taken on line 8—8, Fig. 7. Figure 9 is a fragmentary horizontal section taken on line 9—9, Fig. 8, and showing the pivotal connection and clamping means between one edge of a sash and the adjacent runner bar on an enlarged scale.

70 Similar characters of reference indicate like parts in several views of the drawings.

The frame of the window in the present instance is shown as mounted within the opening of a wall 10 which is constructed of masonry but it is to be understood that this frame may be mounted in a wall constructed of wood or other material. The general elements of the frame consist of two upright jambs 11, 11, a horizontal sill 12 connected at its opposite ends with the lower ends of the jambs, and a horizontal head 13 connected at its opposite ends with the upper ends of the jambs, each of said members being constructed mainly of a single sheet of metal. 80 Each of the jambs is set in a recess 14 in one side of the wall opening and comprises an upright rear plate 15, inner and outer side plates 16, 17, and a front face plate composed of a fixed outer section 18, and a removable inner section 181. The inner side plate 16 is connected directly with the adjacent inner edge of the rear plate 15 and is provided at its front edge with a laterally projecting flange 19 which fits against 85

the adjacent part of the wall. The outer side 17 of the jamb is connected at its rear end with the outer end of the rear plate 15 by a bead or fin 20 projecting backwardly into a slit 21 in the wall and formed by reversely bending or doubling the sheet of metal from which the jamb is formed at the rear outer corner of the same so that the bead or fin is integral with this rear plate and outer plate, as best shown in Fig. 5. The jamb is secured in the recess 14 of the window opening of the wall in this instance by means of mortar or cement 22 applied between the outer plate 17 and the bead 20 of the jamb and the adjacent part of the wall recess. This bead therefore forms a wind break baffle in the joint between the jamb of the window frame and the wall opening which operates to prevent or check any weather from driving into building from the exterior in case the window frame should be imperfectly set when erected or the joint between the frame and wall should become loose from any cause, thereby avoiding the objectionable results which otherwise would follow the entrance of rain, snow, wind or dust into the building at this point. Moreover, this bead strengthens the frame and being made integrally with the jamb does not appreciably add to the cost of the same. The fixed outer section 18 of the face plate of the jamb extends inwardly from the front edge of the outer plate 17 across the front half of the jamb and is stepped so as to form a rabbet 23 constituting part of an outer runway and an outer stop or shoulder 24 and an inner rabbet 25 forming part of a channel shaped seat which is adapted to receive a parting strip or stop arranged between the runways for the upper and lower sashes as will be hereinafter described. The removable section 181 of the jamb face plate is made from a sheet of metal which is bent so that its front side is step shaped and forms an inner rabbet 26 constituting part of an inner upright runway, an inner stop or shoulder 27, and an outer rabbet 28 constituting part of the seat for said parting strip. A hollow sheet metal jamb is thus formed which serves as a box for a vertically movable weight constituting part of the sash balancing mechanism.

Arranged within the hollow jamb are one or more horizontal metal braces 29 each of which is connected at its outer end with the rear side of the fixed section 18 of the jamb face plate and its inner end with the inner side of the inner side plate 16 of the jamb, the connections between these members being preferably effected by electric welding or the like. The central part of each of these braces is spaced apart from the rear sides of the fixed and movable sections of the jamb face plate and at its inner end

each of these braces is provided with an off-set lip 30 which together with the adjacent front edge of the inner side 16 of the jamb forms a pocket or seat 31 in which the adjacent inner edge of the removable inner jamb face plate section 181 is seated and thereby holds these parts in position relative to each other and also produces a neat appearing and finished joint between the same, as shown in Fig. 5. The outer edge of the inner jamb face plate section 181 laps the rear side of the inner edge portion of the outer face plate section 18, and the same is also provided with a reversely bent part or fold 32 which terminates in an inclined bearing lip 33 which projects inwardly and rearwardly and engages with the front side of the braces 29, thereby holding the outer edge of the inner jamb face plate section in position relative to the inner edge of the outer section of the jamb face plate and also facilitating assemblage of the same. The removable face plate section 181 is removably held in place by screws 34 passing through this plate and the braces 29 and bearing with their heads against the outer sides of this plate adjacent to the inner stop 29 and having their threaded ends engaging threaded openings in the braces.

The parting strip or stop 35 is constructed of a single piece of sheet metal to form a hollow channel bar the front side of which is flush with the outer and inner stops 24 and 27 and the rear edges of which are spaced apart and project rearwardly against the front side of the rabbeted inner part 25 of the outer face plate section 18, as shown in Fig. 5, and thereby forming with the stops 24, 27, outer and inner upright runways for the upper and lower sash mountings. The outer and inner rear corners of the parting strip 35 are provided with rabbets 36, 37, respectively, for use in forming a weather tight joint between the upper and lower sash mountings and the jamb, as will presently appear. The overlapping inner edge of the outer face plate section and the outer edge of the inner face plate section having the reversely bent part 32 are detachably connected by screws 38 passing through the same at different points in their length.

In the vertical runways on the face of the jamb are arranged runners or hanging bars which slide vertically therein and form part of the mounting for supporting the sashes at the respective vertical edges thereof. Each of these hanging bars or runners is constructed of sheet metal and provided with an upright front plate 39 and two side plates 40, 41, projecting rearwardly from opposite edges of the front plate 39 and engaging respectively with one side of the parting strip and the inner side of the companion stop 18 or 181 on the jamb. The

side plate 40 of the hanging strip next to a stop 18 or 181 on the jamb is provided on its rear edge with an inturned flange 42 and the companion side plate 41 extends rearwardly through a slot between the parting stop and the jamb face plate and provided at its rear edge with a laterally projecting flange 43 which is arranged in a vertical channel 44 formed between the rabbit 36 or 37 at a rear corner of the parting strip and the adjacent part of the depressed seat on the central part of the opposing face plate of the jamb. By means of this angular extension on the hanging strip 5 the latter is free to slide vertically on the jamb but is held against movement away from the jamb and the driving of weather through the joint between the jamb and hanging strip is also checked.

10 Each of the hanging bars is provided on its front side or bridge with a vertical channel 50 which is formed by pressing the front plate of this bar backwardly between the sides thereof, the rear side of this channel being connected about midway of its height with the side plates of this hanging bar by a transverse brace 51 which is connected with this channel and these side plates by electric welding or otherwise. Se-

15 cured to the front face of each hanging bar by electric welding and extending across the open side of the channel 50 is a face plate 52 which is preferably coextensive with the face of the respective hanging bar and practically forms a part thereof.

20 Upon the outer hanging bars or runners is mounted an outer or upper sash and upon the inner hanging bars or runners is mounted an inner or lower sash. Each of these sashes has two upright side bars or stiles 45 which are pivotally mounted on one pair of corresponding hanging bars. The upper sash has a top rail 46 connecting the stiles of this sash and cooperating with the head of the frame and a lower meeting rail 47 connecting the lower ends of these stiles and the lower sash has an upper meeting rail 48 cooperating with the meeting rail of the upper sash and connecting the upper ends of the stiles of the lower sash and a lower rail 49 cooperating with the sill of the frame and connecting the lower ends of the stiles of the lower sash. Each of the stiles of the upper and lower sashes 25 is of tubular form and made of sheet metal which is bent to form inner and outer plates 53, 54 connected on their front edges by a turn 55, a laterally projecting flange 56 on the rear edge of the outer plate 53, a laterally projecting flange 57 on the rear edge of the inner plate 54, and a face plate 58 folded back from the inner edge of the flange 56 and connected at its outer edge with the flange 56 by welding or otherwise, 30 as shown in Fig. 5. On its inner side the

inner plate of each stile is provided with a rabbet 59 forming a seat for the adjacent edge of the glass pane 60 of the respective sash, said pane being bedded in cement 61 and held in place by means which include 70 a retaining strip 62 engaging with the inner side of the inner plate of the stile and the adjacent edge portion of the glass pane and detachably connected with the inner plate of this stile by screws 63.

75 Each of the stiles of a sash engages its face plate 58 with the face plate 52 of the adjacent hanging bar and is pivotally and frictionally connected therewith by means which are preferably constructed as follows:

80 The numeral 64 represents the shank of a pivot bolt which passes horizontally through the face plates 58 and 52 of the cooperating stile and hanging bar and also through the bottom of the channel 50 and 85 the internal brace 51 on the central part of the same provided with a screw nut 65 at its rear end which bears against the rear side of the brace 51 and having a head 66 at its front end which is arranged in openings 67, 68 formed in the front plate of the stile and the adjacent part of the retaining strip and bearing through a washer 69 against the front side of the stile flange 57, 90 as best shown in Figs. 7, 8 and 9.

95 Arranged within the central part of the channel 50 on the hanging bar is a detent bar 70 preferably of channel form which projects through a vertical slot 71 into engagement with the face plate 58 of the respective stile. The detent bar and stile are firmly pressed together so as to maintain a frictional engagement between the same at all times by a spring means consisting preferably of a bow shaped leaf spring 72 the 100 central part of which has a hole 73 for the reception of the pivot bolt 64 and bears against the bottom of the channel 50 while the opposite ends of this spring bear against the rear side of the detent bar adjacent to 105 110 opposite ends thereof.

115 By these means of mounting each sash the same can be opened and closed by raising and lowering the same with its hanging bar while parallel with the latter during which time the hanging bars slide vertically in the respective runways of the jambs and the sash is also capable of being turned about a horizontal axis on the pivot bolts 64 for controlling the direction in 120 which the air enters the room and also for reversing the sash so as to permit both sides of the glass pane to be cleaned from the inside of the building and thus avoid 125 the hazard attending cleaning the windows from the exterior of the building. The detent bars bear against the stiles with sufficient pressure to produce the requisite friction for holding the sash at whatever angle 130

the same may be adjusted. These means of mounting the sash are strong and durable, the same are not liable to get out of order and the several parts can be readily assembled and taken apart for inspection, adjustment and repairs.

For the purpose of arresting the rotary movement of each sash on its hanging bars when the sash reaches a position parallel or flush with the hanging bars each of the hanging bars has its face plate provided on diagonally opposite parts of its longitudinal edges relative to its axis of rotation with an upper outer stop hook 74, and a lower inner stop hook 75. In the closed position of the sash each upper center stop hook 74 receives the outer edges of the outer flange 56 and the face plate 58 of the respective stile, as shown in Fig. 6, and each of the inner lower stop hooks 75 receives the inner edges of the flange 57 and the face plate 58 of the respective stile, as shown in Figs. 5 and 6, thereby not only stopping the sash when swung shut but also aiding in producing a weather tight joint between the sashes and the hanging strips.

The head 13 of the frame is also made principally of sheet metal in the form of a hollow box which is secured in a recess 76 in the wall above the window opening and comprises a horizontal top plate 77, outer and inner vertical side plates 78, 79 projecting downwardly from the outer and inner edges of the top plate, an outer stop 80 formed by reversely bending the lower edge of the outer plate inwardly and upwardly, a laterally projecting flange 81 arranged at the lower end of the inner plate 79 and engaging with the adjacent part of the wall, and a removable bottom plate 82, an inner stop 83 formed by reversely bending the inner edge of the bottom plate downwardly, inwardly and upwardly, an intermediate stop 84 formed on the central part of the bottom plate by bending a part of this plate downwardly, and a weather sealing channel 85 opening downwardly and formed on the bottom plate by forming an upwardly bent head on said bottom adjacent to the outer side of said intermediate stop. At its outer edge the bottom plate is provided with an upwardly projecting flange 86 which engages with a downwardly opening hook 87 formed on the inner edge of the outer stop 80. Within the hollow head of the frame are arranged transverse braces 88 each of which is connected at its ends by electric welding or otherwise with the inner side of the side plates 78, 79, of the head for the purpose of holding the same in place. The inner ends of these braces are provided with hooks 89 forming seats which are removably engaged by the inner edge 90 of the inner stop 83 of the bottom plate 82. The latter is se-

cured in its operative position with its extreme outer and inner edge portions 86, 90, in engagement with the seats 87, 89 by a screw 91 connecting the central parts of the bottom plate with the corresponding part 70 of the brace, as shown in Fig. 4.

The top rail 46 of the upper sash cooperates with the head of the frame to form a weather tight joint or contact therewith when the window is closed and in its preferred form this top rail is made hollow or tubular of sheet metal and provided with angular outer and inner plates 92, 93, a top plate 94 connected at one edge with the outer edge of the outer side plate 92 and provided so at its inner edge with a laterally projecting flange 95 which is secured by welding or otherwise to the laterally projecting edge portion 96 of the inner plate 93 and forms therewith a rib which enters the channel 85 of the frame head in the closed position of the upper sash and thereby forms a joint therewith whereby weather is prevented from driving through this part of the window. The inner part of the top rail is provided with a rabbet 97 against which the adjacent edge portion of the window pane is held by a retaining strip 98 connected by screws 99 with the adjacent part of the top rail, as shown in Fig. 4.

The sill 12 of the frame is fitted in a rabbit 100 formed in the wall at the lower end of the window opening and is made hollow of sheet metal so as to form a top having an inclined outer part 101 and a level inner part 102 which latter extends partly underneath a window stool 103, inner and outer vertical plates 104, 105 projecting downwardly from the inner and outer edges of the sill top and resting on the wall, and transverse braces 106 arranged within the hollow sill and connected at opposite ends with the inner and outer side plates thereof, as shown in Fig. 4. Projecting upwardly from the sill and preferably from a point in line with the junction of the inclined and level parts of the sill top is a weather rib or head 107 which is preferably formed by doubling or plaiting the adjacent part of the sill top. This rib is spaced outwardly from the outer end of the window stool so as to form an upwardly opening recess between the same.

The lower rail 49 of the lower sash cooperates with the sill of the frame to form a weather tight joint therewith when the lower sash is closed. This rail is also made of sheet metal and of tubular form and comprises inner and outer plates 108, 109 of angular form which are connected at their inner edges, and a bottom plate 110 connected by a laterally projecting doubled part or plait 111 with the lower edge of the inner plate 108 and provided at its outer edge with a downwardly projecting flange 112 which is secured in an upwardly turned hook 100

113 at the lower end of the outer plate 109, as shown in Fig. 4. In the lowered and closed positions of the lower sash the tongue formed by the flange 112 and the hook shaped part 113 of the outer plate 109 engage with the outer side of the rib 107 and the inner part of the plait 111 overhangs the stool 103 so as to check the passage of weather through the window at this point. 5

10 The formation of a weather tight joint at this place is further promoted by a weather strip of sheet metal having a supporting plate 114 secured to the underside of the plait 111 and having its inner and outer edge portions folded or doubled to form an inner plait and an outer plait said inner plait having a fixed ply 115 which projects downwardly from the inner edge of the supporting plate 114 and a flexible ply 116 projecting at an incline upwardly from the lower edge of the fixed ply on the inner side of the same, and said outer plait having an inner fixed ply 117 projecting downwardly from the outer edge of said supporting plate 114 and an outer flexible ply 118 projecting at an angle upwardly from the lower end of the companion fixed ply 117. In the closed position of the lower sash the inner flexible ply 115 engages yieldingly with the stool 103 and the outer flexible ply 118 engages yieldingly with the upstanding rib 107, and thereby forms a tight closure between the sash and the sill of the frame. For the purpose of preventing any water from collecting in the recess on the sill between the stool and the rib 107 the latter is provided with a weep hole 119 adjacent to its base through which any water in said recess flows to the outer inclined top of the sill and 30 escapes. The glass pane 60 of the lower sash engages its lower edge with a rabbet 121 on the inner side of the lower rail and held in place by a retaining strip 122 connected with this rail by screws 123, as shown in 40 Fig. 4.

45 The upper and lower meeting rails are each made of sheet metal in the form of tubes and consist of inner and outer side plates 124, 125 connected at their inner ends, and 50 laterally projecting flanges 126, 127 arranged at the outer edges of said plates and connected with each other by welding or otherwise. One of the flanges of the upper meeting rail, preferably the upper one, is provided at its 55 inner edge with an upwardly opening channel 128, and one of the flanges of the lower meeting rail, preferably the upper one, is provided at its outer edge with a depending tongue 129 which is adapted in the closed 60 position of the sashes to engage with said channel and thereby form a weather tight joint between the sashes, as shown in Fig. 4. These meeting rails are provided on their inner sides with rabbets 130 in which the 65 window panes are held by retaining strips

131 connected with the meeting rails by screws 132.

70 Adjacent to opposite ends of the overlapping parts of the meeting rails, closure blocks 133 are secured to the face plates of the frame jambs in order to fill the space at this place between the hanging bars and prevent weather from driving into the building.

75 Improved means are provided for counterbalancing the weight of the sashes to facilitate opening and closing of the same which means are preferably constructed as follows:

80 The numerals 134, 135 represent two sash balancing weights which are vertically movable, respectively, in the hollow jambs of the window frame which form weight boxes for this purpose. One of these weights is connected with opposite hanging bars of one sash and the other weight is connected 85 with the opposite hanging bars of the other sash so that only one weight is utilized for counterbalancing each sash. In the preferred construction each of these weights is connected at its upper end with the upper 90 ends of the hanging bars of the respective sash by two lines 136, 137 having preferably the form of chains, which lines are suitably guided in the frame. In the present case the line 136 which connects each weight with the 95 near hanging bar passes around a guide pulley 138 arranged within the upper corner of the frame on the same side as the frame, thereby providing front and rear stretches of this line which depend on opposite sides 100 of the pulley and connect at their lower ends with the near hanging bar and the respective sash weight. The other line 137 which connects with the far hanging bar passes around a guide pulley 139 arranged adjacent to the pulley 138 and also around another pulley 140 arranged within the frame at the opposite upper corner thereof, so that this line forms a horizontal upper stretch extending between the pulleys 139 and 140 and arranged within the head of the frame, and 105 two end stretches depending from these pulleys and arranged within the jambs of the frame and connected, respectively, with the sash weight and the far hanging bar. The 110 group of pulleys 138, 139 and 140 in each corner of the frame are arranged obliquely and the angle of obliquity of one group is opposite to but parallel with the other group 115 for the purpose of permitting the lines of the two sash hanging bars to pass each other and still permit of attaching these lines to the respective weights and hanging bar to ensure proper supporting of the latter and guiding of the lines. Although these guide 120 pulleys may be mounted in any suitable manner, this is preferably accomplished by pivotally mounting each group of pulleys on a bracket 141 which is secured to the inner 125 side of the jamb and head of the window 130

frame at one of the upper corners thereof, as shown, for example, in Figs. 2 and 4.

As a whole this window is very strong and durable and will retain its form under the 5 roughest usage to which the same may be subjected. It also can be very easily manipulated for either raising or lowering the sash or tilting the same into various angles and when closed the same is weather tight to a 10 maximum extent and thereby permits of economically regulating the temperature of the building and also controlling the ventilation of the same.

I claim as my invention:

15 1. A window comprising a frame having a jamb, stops arranged on the jamb, a parting strip arranged on the jamb and forming with the same and said stops vertical runways, and means for mounting sashes 20 on the jamb including hanging strips carrying the sashes and sliding vertically in said runways and provided with parts extending across the joint between said parting strip and the jamb.

25 2. A window comprising a frame having a jamb provided on its face with a vertical channel seat and stops on opposite sides of said seat, a parting strip secured in said seat and forming with said stops vertical runways and provided on its rear corners 30 within said seat with rabbets, and sash hanging bars sliding in said runways and each provided with an angular extension 35 which passes between the parting strip and the face plate of the jamb and enters a channel formed by said seat and the opposing rabbet on the parting strip.

40 3. A window comprising a frame having a runway and a runner or hanging bar forming part of a sash mounting and slidable lengthwise in said runway and having a front plate, side plates extending rearwardly from the edges of the front plate, and a channel arranged on the front plate, and a 45 face plate secured to the front side of said front plate and extending across said channel.

45 4. A window comprising a frame having a runway, a hanging bar slidable lengthwise in said runway and having side plates, a channel on its front part and a face plate extending across said channel, a sash for supporting a pane having a tubular stile having an inner plate and an outer and a 55 face plate connecting said inner and outer plates and bearing against the face plate of said hanging bar, and a retaining strip adapted to engage the pane and secured to said inner plate of the stile.

60 5. A window comprising a frame having a runway, a hanging bar slidable lengthwise in said runway and having side plates, a channel on its front part and a face plate extending across said channel, a sash for 65 supporting a pane having a tubular stile

having an inner plate and an outer and a face plate connecting said inner and outer plates and bearing against the face plate of said hanging bar, and a retaining strip adapted to engage the pane and secured to 70 said inner plate of the stile.

6. A window having a frame provided with a runway, a hanging bar slidable lengthwise in said runway and having side plates, a front plate, a channel in said front plate and a face plate secured to the front side of said front plate and having a slot, a sash for supporting a pane having a stile provided with a face plate engaging with the face plate of the hanging bar, a detent 80 bar arranged in said channel and projecting through said slot into engagement with the face plate of said stile, means for yieldingly pressing said detent bar against said stile, and means for pivotally connecting 85 said stile and hanging bar.

7. A window having a frame provided with a runway, a hanging bar slidable lengthwise in said runway and having side plates, a front plate, a channel in said front plate and a face plate secured to the front side of said front plate and having a slot, a sash for supporting a pane having a stile provided with a face plate engaging with the face plate of the hanging bar, a detent 90 bar arranged in said channel and projecting through said slot into engagement with the face plate of said stile, a bow leaf spring arranged within said channel and bearing with its central part against the bottom 95 of said channel and engaging its ends with the ends of said detent bar, and a pivot bolt passing through said face plates, channel and spring.

8. A window having a frame provided with a runway, a hanging bar slidable lengthwise in said runway and having side plates, a front plate, a channel in said front plate and a face plate secured to the front side of said front plate and having a slot, a 100 sash for supporting a pane having a stile provided with a face plate engaging with the face plate of the hanging bar, a detent bar arranged in said channel and projecting through said slot into engagement with the 105 face plate of said stile, a bow leaf spring arranged within said channel and bearing with its central part against the bottom of said channel and engaging its ends with the ends of said detent bar, and a pivot bolt 110 passing through said face plates, channel and spring, and having a screw nut arranged in rear of the channel and a head arranged within the stile.

In testimony whereof I affix my signature. 125
EDWIN WILLIAM ABRAHAMSON.
